SUPPLEMENTAL SEAT FOR A CHILD'S CHAIR
OR THE LIKE

Ernest C. Free, Salem, Oreg.

Application November 30, 1954, Serial No. 33,341

Term of patent 14 years

(Cl. D15—1)

Fig. 1

Fig. 4

Fig. 2

Fig. 3

Figure 1 is a view in perspective of the supplemental seat for a child's chair or the like;

Figure 4 is a top plan view of the supplemental seat for a child's chair or the like; and

I claim:

The ornamental design for a supplemental seat for a child's chair or the like, as shown.
